HEAT RETAINING COVER

Grace Miller, Tallahassee, Fla.

Application August 9, 1955, Serial No. 527,220

1 Claim. (Cl. 312—284)

This invention relates to covers for retaining heat, particularly those for placing over food on a plate which is to be transported an appreciable distance from the kitchen. It will have particular usefulness in hospital service where the equipment receives rough treatment in the hands of poorly paid employees.

An important object of the invention is to provide a double-walled cover of heat-retaining type which has an inside surface free from cracks or crevices which could collect bacteria and an outside surface minimizing passage of heat from the space between the walls.

A still further object of the invention is to provide a heat-retaining air space type cover highly suitable for hospital use in which the two main parts can readily be separated for separate sterilization and which, if the outer plastic cover should be broken, it can readily be replaced for use with the old inner metal ceiling or dome of the cover.

In the drawings:

Figure 1 is a central vertical section.

Figure 2 is an enlarged fragmentary sectional view of the peripheral joint.

Figure 3 is a modification.

The cover consists of two spaced walls, each of a single piece of material of substantially uniform thickness, and means for detachably connecting the two parts together so as to provide a heat insulating space between the two walls or domes, the securing means preferably being operable without any tools and the entire cover being so made that there will be no crevices in which food particles might be caught, as the device, although having general use, is designed primarily for service in hospitals where it is important that the cover be very easy to sterilize and where, as here, the outer cover is relatively breakable with respect to the inner cover so that a new cover can readily be assembled with the other portions. To this end an inner dome 10 is formed of a metal which could be Monel metal, stainless steel, etc., but is preferably aluminum of a rather high density. This inner shell can be of any normal shape commonly used for double-walled covers of this type. It is my preference that the central top surface 11 be very slightly curved on an extremely large spherical radius, although actually it can be perfectly flat. Likewise, the side walls 12 would follow a curved formation if the top were spherical, but for ease of manufacturing and for obtaining maximum space within the cover the side wall is made substantially a cylinder as illustrated. Whatever the shape of the metal of the top and the sides, the upper circular junction as at 14 should be a smooth curve.

The outer wall or dome 20 corresponds generally in shape to the inside dome 10 but to increase the space between the two walls of the cover I prefer that the distance apart of the two walls at the vertical axis shall be greater than the space 21 near the circular top edge of the cover, this space 21 being approximately the same transverse dimension as the space 22 along the sloping or ver-

2

tical sides of the cover between the two walls. It is quite important to make the walls of the cover of quite different materials and, hence, the outer dome 20 is preferably of a plastic material having a high heat insulating value, preferably one that will take a smooth finish on the outside and thick enough to take quite a bit of abuse without damage. The inside surface 15 of the inner dome is preferably highly polished, mirrored as often expressed, as this will reflect heat back to the food 30 on plate 31.

10 As a preferable means for joining the two domes together, a screw 33 is permanently carried by the inner dome 10 and extends loosely through the plastic outer dome 20. The handle 34 of the cover is of either metal or plastic and is internally threaded as at 35 to serve as a nut to bring the two domes into firm contact at the junction of their lower peripheral edges and yet be quickly removable without tools for separate sterilization of the two parts whenever that might be required or for replacement of a broken outer cover.

15 This peripheral joint at the bottom of the cover is of great importance. It is my preference that the inner metal dome 10 shall curve as at 16, ending in a cylindrical face 17 even with the outer surface 24 of the outer dome. By having the metal project to the margin of the outer cover, 20 we will lose a very slight amount of heat to the atmosphere, but in a device of this kind durability is much more of a concern than the very slight loss in heat. By having the metal edge 17 below the outer dome, the latter is given a very much greater life as the blows that normally 25 destroy an outer cover are received at the bottom circular edge of the cover and such blows will all be taken by the metal and not by the more easily damaged plastic shell or dome.

20 This peripheral joint at the bottom of the cover is of great importance. It is my preference that the inner metal dome 10 shall curve as at 16, ending in a cylindrical face 17 even with the outer surface 24 of the outer dome. By having the metal project to the margin of the outer cover, 25 we will lose a very slight amount of heat to the atmosphere, but in a device of this kind durability is much more of a concern than the very slight loss in heat. By having the metal edge 17 below the outer dome, the latter is given a very much greater life as the blows that normally 30 destroy an outer cover are received at the bottom circular edge of the cover and such blows will all be taken by the metal and not by the more easily damaged plastic shell or dome.

The plastic outer dome 20 is molded in such fashion as 35 to provide an enlargement 25 having at its bottom a flat annular shoulder 26 which will be in light contact with a similar annular shoulder 18 on the metal inner dome when the parts are assembled. From the inner edge of the shoulder to the outside margin of the cover both domes have matching curves 27 which first make contact as the handle 34 is screwed down, the flat co-planar surfaces 18 and 26 forming a stop so that when these flat surfaces 18 and 26 are in firm contact the outer cylindrical walls 17 and 24 are in perfect registry. It will be noted that the inner face of the cover that could get in contact with the food is a smooth, unbroken surface having no joint or crack of any kind, the screw 33 being secured to the upper surface of the dome and not extending down as far as the mirrored surface 15.

40 In the modification shown in Figure 3, the outer plastic shell is much the same as before but its skirt 40 directly touches the serving dish 31 and the metallic portion of the cover is quite restricted in size, consisting of an outer metal disk 41 and an inner metal disk 42, the latter being 45 the bottom wall of the upper air space of the cover. Each of the plates 41 and 42 are highly polished or mirrored on their lower surfaces and they are spaced by a separating ring 45 which makes a snug fit with the skirt 40 which is preferably conical. The mirrored surface of disk 42 reflects heat downwardly toward the food and this surface is not affected by the steam which would collect on the bottom surface of plate 41. The screw 33 is secured to both disks. In using this modification, it is proposed 50 to use a strong, tough plastic shell.

What I claim is:

A double-walled heat retaining cover for food served on a plate in which the two walls are normally secured together to form a single unit, said cover having an outer 55 wall of a heat insulating plastic having the general shape of a dome with a roof and a skirt, the outer surface of 60 said cover being a smoothly curved surface of revolution.

tion ending in a circular lower edge, and the inner wall of the cover comprises a metal member fitting the outer dome in a zone of contact bounded by a surface of revolution and having a mirrored surface parallel to the plane of the open lower circular edge of the cover to reflect heat back to the food on the plate, said metal inner wall having a peripheral edge which underlies the circular lower edge of the plastic outer wall, whereby when the walls are assembled, the plastic outer wall is protected against breakage from a blow on the lower outside edge of the cover by the underlying metal edge, and readily separable threaded means for securing together the plastic outer wall and the metal inner wall in an air-tight manner to form a dead air space between them, said threaded means providing for ready manual separation of the parts for independent cleaning, the surface of the inner wall in contact with vapor from hot food within the cover being smooth and unbroken, thus avoiding any possibility of crevices that might collect bacteria, so that the cover is particularly suitable for hospital service.
